UNITED STATES PATENT OFFICE.

SAMUEL JENKINSON, OF ROCHESTER, NEW YORK.

SASH-BALANCE.

SPECIFICATION forming part of Letters Patent No. 432,137, dated July 15, 1890.

Application filed January 6, 1890. Serial No. 335,960. (No model.)

To all whom it may concern:

Be it known that I, SAMUEL JENKINSON, of Rochester, in the county of Monroe and State of New York, have invented a new and useful Improvement in Sash-Balances, which improvement is fully set forth in the following specification, and shown in the accompanying drawings.

My invention relates to that class of sash-balances in which the sash is held by cords wound upon spring-actuated drums, the cords passing over idle-pulleys above the respective drums.

The object of the invention is to provide an improved method of guiding or carrying the cord, to provide an improved and better brake for modifying the action of the spring-drum, and regulate the running of the cord on and off the drum. The invention is hereinafter fully described, and more particularly pointed out in the claims.

Referring to the drawings, Figure 1 is a side elevation of a part of a window sash and casing with my improved sash-balance in place, numerous parts being broken away and vertically sectioned; Fig. 2, a view of the sash-balance seen, as indicated by arrow *x*, in Fig. 1, parts being broken away and the frame vertically sectioned, as on the dotted line *y* in Fig. 3, parts being shown in two positions by full and dotted lines; Fig. 3, a view of the device seen, as indicated by arrow *z*, in Fig. 1; Fig. 4, a side elevation of a portion of the frame of the device. Fig. 5, drawn to a larger scale, shows one of the bearing-faces of the brake, a part of the rubbing piece being broken away; and Fig. 6, drawn to a still larger scale, is a cross-section taken on the dotted line *x'* in Fig. 5.

Referring to the parts, A is the sash, and B the casing of the window, both of common construction.

C is my improved sash-balance set in a cavity *a* in the casing, in the usual manner, and held to place by ordinary screws *b*.

c is the frame of the device, and *d* the face-plate. D is a spring-actuated drum, substantially of common construction, held within the frame by axial projections *e*, in the usual manner.

f is the suspending-cord wound upon the

drum in circumferential spiral grooves *g*. The cord passes over a grooved idle-pulley *h* within the frame, held to turn freely upon a horizontal shaft *i*, rigid with the frame, and to move laterally thereon from side to side of the frame. The cord is attached to the sash by an ordinary fastening device *k*.

l is a brake divided at its upper end and held to bear upon the conical or inclined surfaces *n* *n* of the idle-pulley. The brake is held to turn upon a rigid horizontal pin *o* and is fitted to slide laterally thereon.

p is an adjusting-screw for the brake, passing freely through the lower end of the brake. This screw passes through a side of the frame in which it has a bearing, there being an opening *r* in the face plate to make way for the head of the screw.

s is a nut for the screw, with its reduced ends resting in horizontal slots *t* *t* in the opposing sides of the frame.

u is a coiled spring upon the adjusting-screw between the nut and the brake, acting to press the latter against the idle-pulley. By turning the screw into the nut the latter will be drawn toward the brake, thus compressing the spring and causing it to press the brake more firmly against the idle-pulley. A reverse motion of the adjusting-screw will cause the brake to bear less heavily upon the idle-pulley.

The inner opposing faces of the brake that bear against the idle-pulley, are provided with yielding friction-pieces *v*, Figs. 5 and 6, to bear directly upon the surfaces of said pulley. These friction-pieces, which may be of leather, india-rubber, and cloth, or similar material, are set into dovetailed depressions *w*, as shown, and project beyond the respective faces of the brake.

As the cord winds upon or unwinds from the actuating-drum D, it moves from side to side thereof, on account of the spiral form it takes upon the drum, and the idle-pulley moves laterally, as stated, to accommodate itself to the position of the cord. The upper end of the brake also moves laterally with the idle-pulley, this motion being permitted on account of the hole *a'* therein being made flaring in a vertical direction from the middle point to the extremities, as shown in Figs.

1 and 2. These motions of the brake are radial, it turning upon the screw p as a pivot or center.

I find in practice that it is advantageous to 5 apply the brake to the idle-pulley rather than to the drum or cord, as is usually done. The idle-pulley revolves more rapidly than the drum in proportion to the difference in the two diameters and a much less brake-pressure 10 applied to the idle-pulley is needed to regulate the motion of the parts than if applied to the drum or the cord.

It will be understood that on account of the 15 idle-pulley being shiftable upon its shaft, as stated, when in different positions, its plane if extended would cut the drum at different places.

What I claim as my invention is—

1. In a sash-balance, an actuating-drum 20 and a suspending-cord on the drum, in combination with a laterally-movable idle-pulley and a brake pressing said idle-pulley, substantially as described.

2. The combination, in a sash-balance, of an 25 actuating drum and a suspending-cord, with an idle-pulley for the cord, a brake for the

idle-pulley, and an adjuster for the brake, substantially as described and shown.

3. In a sash-balance, a drum and a cord, in combination with an idle-pulley formed 30 with conical or inclined sides and a divided brake to bear upon said inclined sides, substantially as shown.

4. In combination with the drum and the cord of a sash-balance, a laterally-movable 35 idle-pulley, and a brake bearing upon said idle-pulley, said brake being constructed to turn or swing upon a pivot to keep with the idle-pulley, substantially as shown and set forth.

5. In combination with the drum and the cord of a sash-balance, an idle-pulley and a brake mechanism for said pulley, consisting of a brake proper, an adjusting-screw, a pressure-spring, and a nut, substantially as shown. 45

In witness whereof I have hereunto set my hand this 23d day of December, 1889, in the presence of two subscribing witnesses.

SAMUEL JENKINSON.
